D. W. BUNKER.
HEEL BREASTING MACHINE.
APPLICATION FILED DEC. 26, 1918.

Patented Aug. 22, 1922.

INVENTOR -
Julius W. Bunker

UNITED STATES PATENT OFFICE.

DARIUS W. BUNKER, OF BROOKLINE, MASSACHUSETTS, ASSIGNOR TO UNITED SHOE MACHINERY CORPORATION, OF PATERSON, NEW JERSEY, A CORPORATION OF NEW JERSEY.

HEEL-BREASTING MACHINE.

1,426,354.

Specification of Letters Patent. Patented Aug. 22, 1922.

Application filed December 26, 1918. Serial No. 268,289.

To all whom it may concern:

Be it known that I, DARIUS W. BUNKER, a citizen of the United States, residing at Brookline, in the county of Norfolk and 5 State of Massachusetts, have invented certain Improvements in Heel-Breasting Machines, of which the following description, in connection with the accompanying drawings, is a specification, like reference characters 10 on the drawings indicating like parts in the several figures.

This invention relates to machines for 15 breasting heels, and particularly to machines of the type disclosed in United States Letters Patent No. 784,340, granted March 7, 1905, upon an application of B. F. Mayo, for breasting Louis heels.

Machines of this type comprise a rotary 20 cutter and a shoe support or rest which engages the tread face of the heel and preferably the bottom of the forepart of the shoe, against which rest the shoe is held in the hands of the operator. The shoe rest and cutter are then moved relatively to cause 25 the cutter to trim the breast of the heel from side to side of the heel. To position the shoe longitudinally a rib is provided on the part 30 of the support which engages the tread face of the heel against which the breast edge of the top lift of the shoe is held by the operator, the rib preventing movement of the shoe toward the cutter. The rib is necessarily very low in order to expose as much 35 as possible of the breast face of the heel to the action of the cutter.

In the use of machines of this type, it sometimes happens that the cutter, when it engages the shoe, causes dislodgment of the shoe heel from the positioning rib and draws 40 the shoe and the hand of the operator, which must grasp the rear part of the shoe to hold the shoe against the rib, into the cutter, causing the shoe to be injured or spoiled and sometimes the hand of the operator to be 45 badly lacerated.

Objects of this invention are to provide a machine which, while retaining the many highly desirable and valuable features of machines of the aforesaid type, will insure adequate protection to the operator from injury 50 by the cutter, and to provide improved means for locating and holding the shoe during the operation of the cutter.

A feature of the invention consists in a 55 novel organization including a rotary cut-

ter and a shoe rest against which the shoe is held by the operator during relative movement of the shoe and cutter to effect the cutting action of the cutter upon the shoe with means held from movement relatively to the 60 shoe rest constructed and arranged to prevent movement of the operator's hand toward the cutter. The said means is preferably constructed and arranged to embrace the heel of the shoe and to be opened and 65 closed by means under control of the operator, for example, as shown, as an incident to the operation of means, such as a treadle which is provided for effecting relative movement of the cutter and the shoe to cause 70 the cutter to act upon the shoe. While it is not essential that the heel shall be engaged by the embracing means but only that means shall be provided between the cutter and the operator's hand to prevent movement of 75 the hand and shoe into the cutter, it is preferable that the embracing means be constituted as means to hold the shoe. The heel embracing means, in the construction shown, 80 comprises a pair of jaws which is closed upon the heel, one or both of the jaws being arranged for closing movement upon the heel as an incident to the operation of effecting relative movement between the cutter and the heel tread support. As shown 85 herein, the heel tread support is movable to carry the shoe past the cutter, and the force required for this movement is utilized to press the jaws upon the heel. Only one of the jaws need be movable relatively to the 90 heel and in the construction shown the upper jaw is so movable, the shoe being rested against the lower jaw and the upper jaw operated to hold the heel. By this arrangement the lower jaw has a constant 95 limit of movement irrespectively of the width of the heel being treated and that limit is such that the lower edge of the heel will be carried to a point opposite the axis of the cutter and no farther. This prevents any 100 operation of the cutter upon the heel during its return movement, such second operation being undesirable.

It is a usual practice to scallop the heels prior to their being breasted. The term 105 "scallop" in this connection refers to the concavity formed in the breast face of the heel in the portion adjacent to the tread face. The scalloping operation gives a pointed formation to the breast corners of 110

the top lift and in the breasting operation the cutters should act up to these corners without cutting anything off of them. This is impossible in machines of the prior construction since the rib on the tread plate prevents the cutter from acting up to the corners of the top lift.

A further feature of the present invention consists in gaging mechanism for the heel 10 breast which permits operation of the cutter up to the corners of the top lift. This mechanism, as shown, comprises a gage which engages only the central portion of the breast and hence may lie in the scallop of the 15 top lift out of the way of the cutter. The space in the scallop is ample to accommodate a gage of substantial proportions and to afford a good support for the heel and give it a positive longitudinal location relatively 20 to the cutter.

Another feature of the invention consists in means for locating the gage centrally of the breast irrespectively of the width of the heel. By this construction the gage is all 25 ways located in the deepest part of the scallop and causes heels of different widths to be held in the same longitudinal position relatively to the cutter. The position of the gage is preferably controlled by the position 30 of the jaws which embrace the heel and, in the construction shown, operative connections are provided between the movable jaw and the gage which maintain the gage centrally between the jaws irrespectively of 35 the space between the jaws and hence irrespectively of the width of the heel held by the jaws.

These and other features of the invention will appear more fully from the following 40 detailed description when read in connection with the accompanying drawing and will be pointed out in the appended claims.

In the drawing,—

Fig. 1 is a perspective view of the head 45 of the machine, part of the column on which it is mounted being omitted;

Fig. 2 is a perspective view of the mechanism shown in Fig. 1 taken from the rear side;

Fig. 3 is an elevational detail of parts shown in Fig. 2; and

Fig. 4 is a perspective view of a shoe in the shoe positioning means shown in Fig. 1.

Referring to Fig. 1, the numeral 2 indicates the column of the machine upon the upper portion of which is a head 4 having bearings 6, 8 for a cutter shaft 10 driven from a pulley 12. On one end of the shaft 10 is a cutter head 14 having two fly cutters 16, the cutting portions of which are shaped to give the proper contour to the breast portion of a Louis heel. The work support comprises a post 18 splined for vertical movement in a sleeve 20 formed on a member 22 60 which has a dovetailed portion arranged to

slide horizontally in a projection 24. The projection 24 is part of a bracket 26 which is secured by screws 28 to the head 4. The screws 28 pass through slots 30 in the bracket 26, and by reason of this connection the 70 bracket 26 may be adjusted heightwise of the heel in a direction at right angles to the direction of movement of the slide 22 in the projection 24 and also transversely of the cutter shaft. By this adjustment the action 75 of the cutter relatively to the shank portion of the heel may be controlled. To provide a fine adjustment of the support in this direction a screw 25 is provided which is threaded through the bracket 26 and engages 80 the machine frame. Adjustment of the slide 22 lengthwise of the cutter shaft 10 to control the depth of cut lengthwise of the heel is effected by means of a screw 32 mounted for rotation in a plate 34 attached to the 85 projection 24 and threaded into the slide 22. To hold the slide securely in adjusted position, a hand nut 36 is provided which is threaded upon a screw stud 37 secured to the projection 24 and passing through a slot 90 38 in the slide 22.

On the upper end of the post 18 is secured a head 40 which carries the shoe positioning and holding mechanism. The head 40 has an arm 42 provided with a split clamp 44 95 which receives the stem 46 of a forepart rest 48. Another arm 50 of the head 40 extends upwardly and is formed with a surface 52 having a raised ledge 53 to engage the side of a heel attached to a shoe near its tread face. The tread face of the heel engages a tread rest 55 carried by the arm 50. Extending downwardly and toward the toe of the shoe from the surface 52 is a flange 54 against which the finger of the operator's 100 hand may rest. Above the surface 52 is a member 56 having a surface complementary to the surface 52, a ledge 57 corresponding to the ledge 53 and a flange 58 similar to the flange 54. The member 56 is arranged for 105 movement vertically toward and from the surface 52 as follows: On the arm 50 is a vertically upstanding portion 60 (Figs. 2 and 3) and on the member 56 is a part 62 extending downwardly between the portion 110 60 and a part 64 formed to provide a vertical guide for the part 62. A lever 66 is fulcrumed at 68 to the upstanding portion 60 and has a slightly elongated hole at one end which engages a pin 70 fixed in the part 115 62 and extending through a slot 72 in the part 64. The lever 66 is operated by a connecting rod 74 extending to a treadle 76 mounted in a convenient position of the floor. Operation of the treadle causes the member 56 120 125 having the ledge 57 which constitutes a movable jaw to move toward and from the ledge 53 on the surface 52 which constitutes a fixed jaw, and when the jaws have clamped a heel between them further upward pressure on 130

the rod 74 by the treadle 76 causes the post 18 to slide upwardly in its sleeve 20 carrying with it, of course, the jaws, shoe positioning means 48 and shoe, thus subjecting the 5 heel of the shoe to the action of the cutter blades 16.

The jaws 52, 56 are formed as shown to surround the entire heel except its breast portion but permit the operator to retain 10 hold on the rear portion of the shoe. The flanges 54, 58 prevent any possible approach of the operator's finger toward the cutter. As a whole the device absolutely protects 15 the operator's hand from possible contact with the cutter and effectively locates and holds the shoe heel during the breasting operation.

To position the shoe heel longitudinally for the action of the cutter, it is desirable to 20 provide a gage or stop for the breast edge of the top lift. In the construction shown, such a gage is provided by a projection 80 formed on the inner edge of the part 64 and extending across the inner edge of the part 25 60, as best shown in Fig. 4. The projection 80 is preferably provided with a notch engaging and adapted to slide along the edge of the part 60, which is reduced in thickness by a rabbet 82. The projection 80 extends 30 sufficiently above the tread rest 55 which is engaged by the tread face of the top lift of the heel to provide a stop or gage for the breast edge of the top lift. In case the heel is formed with a concavity or scallop in the 35 portion of the breast prior to the breasting operation, which is a common practice, the projection will be located in the scallop and may be of substantial dimensions to afford a secure support for the heel. The gage 80 in 40 this case should always be positioned centrally of the scallop of the heel irrespectively of the width of the heel, so that heels of different widths will be positioned uniformly with respect to the cutter. Hence in the 45 construction shown means is provided for locating the gage 80 centrally of the heel breast, whatever its width may be. To effect this, the part 64, including the projection 80, is arranged for vertical sliding movement, 50 which movement is effected from the lever 66 by means of a pin 84 fixed in the part 64 and extending through a slightly elongated hole 86 in the lever 66. The pin 84 is located midway between the pivot 68 of the lever 55 and the pin 70, which communicates movement to the jaw 56, and hence the movement of the projection 80 will always be half as great as that of the jaw 56, and the projection 80 will be located in the center of the 60 heel breast of a heel held between the jaws 52, 56. The projection or gage 80 is designed to be completely contained in the scallop of the heel, and hence the heel is so exposed to the action of the cutter that it may cut 65 completely to the corners of the top lift. In

the machine of the prior patent above referred to this is impossible because the positioning rib extends across the entire breast face of the top lift.

During the later part of the action of the 70 cutter upon the heel, it is desirable to retard the movement of the shoe so that the cutter will cut clean on the lower edge of the breast where the cut is completed. To effect this, the post 18 is extended downwardly and 75 carries a sliding sleeve 90 having a flange 92. Between the flange 92 and a thumb nut 93 threaded on the lower end of the post 18 is a spring 94. When the work support has been raised and the knife is about to complete its cut, the sleeve 91 engages the sleeve 20, making it necessary to compress spring 80 94 in order to effect further movement of the work. The operator, therefore, is obliged to finish the cut at a slower rate, 85 with the result that a clean edge is formed on the lower edge of the breast. A construction similar to this is disclosed and claimed in an application for United States Letters Patent Serial No. 107,430, filed July 3, 1916, 90 by Daniel E. Quinlan.

Preferably the movement of the support is limited at a point such that the face of the ledge 53 which engages the lower side of the heel will be at the same height as the center 95 of the shaft 10. This prevents any action of the cutter upon the heel during the return movement of the shoe. To effect this a pin 96 is provided in the post 18 which lies in a slot formed in the sleeve 90, and when the 100 sleeve 90 is depressed engages the sleeve 20 to limit movement of the post.

The machine is provided with a cutter guard 100 which is lifted as the shoe is raised by a link 102 connecting the guard to the 105 work support. The link 102 at its lower end is provided with a slot 104 through which passes a screw 105 which is threaded into a block 107 pivoted to a projection 106 from the head 40. By this construction the relation of the guard 100 to the work support 110 may be varied.

In the operation of the machine, the operator grasps a shoe by its toe and about the rear part and places the forepart of the sole 115 against the rest 48 and the heel between the ledges 53, 57 on the jaws 52, 56 with the lower side of the heel resting on the ledge 53. The jaw 56 is then moved, by tipping of the treadle 76, toward the jaw 52 and at 120 the same time the shoe is pushed forwardly against the rest 80 which is automatically located at the center of the heel, as the jaw 56 reaches the heel, and lies in the scallop 125 of the breast. The treadle is now further operated to raise the shoe together with its holding and positioning mechanism, the raising force being transmitted from jaw to jaw through the heel and causing the shoe to be firmly held between the jaws dur- 130

ing the passage of the heel across the cutter, the jaw closing being effected as an incident to the act of raising the shoe support. The cutter acts upon the heel, of course, from side to side of the heel and finishes its cut on the lower edge of the heel breast. When the shoe has reached a position such that the cut is about to be finished, the flange 92 engages the sleeve 20, causing the spring 94 to be compressed, the action of the spring being to slow down the movement of the shoe as the cut is finished and to cause a clean cut to be made on the lower edge of the heel breast.

15 When the shoe reaches a position such that the surface of the ledge 53, on which the lower side of the heel rests, is in a horizontal plane passing through the axis of the cutter, the pin 93 in the post 18 engages the sleeve 20 and arrests further movement of the shoe. This prevents movement of the heel past the axis of the cutter and prevents any action of the cutter upon the heel during the return movement of the shoe which is now allowed 25 to take place by releasing the upward pressure on the treadle rod 74.

Having thus described my invention, what I claim as new and desire to secure by Letters Patent of the United States is:

30 1. In a machine of the class described, the combination of a rotary cutter, a shoe rest against which a shoe is held by the hand of the operator, means for relatively moving the cutter and the rest to cause operation 35 of the cutter upon the breast of the heel of the shoe, and means arranged above the shoe between the operator's hand and the cutter and held from vertical movement relatively to the shoe and rest to prevent 40 movement of the hand of the operator toward the cutter in case the shoe should be drawn toward the cutter.

2. In a machine of the class described, the combination of a rotary cutter, a shoe rest against which a shoe is held by the hand of the operator, means for relatively moving the cutter and the rest to cause operation 45 of the cutter upon the breast of the heel of the shoe, and means mounted on the rest and extending above and below the shoe in close relation thereto to protect the operator's hand which holds the rear end of the shoe from movement toward the cutter in case the shoe should slip on the rest.

50 3. In a machine of the class described, the combination of a rotary cutter, a shoe rest against which a shoe is held by the hand of the operator, means for relatively moving the cutter and the rest to cause operation 55 of the cutter upon the breast of the heel of the shoe, and means for embracing the heel and preventing movement of the hand of the operator toward the cutter in case the shoe becomes displaced upon the 60 rest.

65

4. In a machine of the class described, the combination of a power operated cutter, a rest adapted to receive the tread face of a shoe heel presented thereto in the hand of the operator, means for relatively moving the rest and the cutter to effect operation of the cutter upon the breast of the heel of the shoe, and means surrounding the heel and located between the operator's hand and the rest to prevent the hand from being drawn into the cutter in case the heel should slip on the rest.

5. In a machine of the class described, the combination of a rotary cutter, a rest for the tread face of the heel, means for relatively moving the cutter and rest to cause operation of the cutter upon the breast of the heel of a shoe, means for embracing the heel of the shoe constructed and arranged to hold the heel during the operation of the cutter, and means operated as an incident to the relative movement of the rest and cutter to force the embracing means against the heel.

6. In a machine of the class described, the combination of a rotary cutter, a rest for the tread face of the heel, means for relatively moving the cutter and rest to cause operation of the cutter upon the breast of the heel of a shoe, and means operated by said moving means for holding the shoe upon the rest.

7. In a machine of the class described, the combination of a rotary cutter, a rest for the tread face of the heel, means for relatively moving the cutter and rest to cause operation of the cutter upon the breast of the heel of a shoe, a pair of jaws for engaging the heel of the shoe, and means operated by said moving means for causing the jaws to hold the heel.

8. In a machine of the class described, the combination of a rotary cutter, a rest for the tread face of the heel, manually operated means for moving the shoe past the cutter to cause the cutter to breast the heel, holding means arranged to close against the sides of the heel, and means operated by said manually operated means for closing the holding means.

9. In a machine of the class described, the combination of a rotary cutter, a rest for the tread face of the heel, holding means arranged to close against the sides of the heel to hold the heel upon the rest, and manual means operating first to close the holding means and then to move relatively the shoe and cutter to cause operation of the cutter upon the heel breast.

10. In a machine of the class described, the combination of a rotary cutter, a rest for the tread face of the heel movable past the cutter, holding means arranged to close against the sides of the heel to hold the heel upon the rest, and means operating

first to close the holding means and then to move the rest and holding means past the cutter to cause the cutter to act upon the heel breast.

5 11. In a machine of the class described, the combination of a cutter, a rest for the tread face of the heel, shoe holding jaws on the rest, means for moving relatively the cutter and rest to cause the cutter to operate on the breast of the heel of the shoe, and means operated as an incident to said relative movement for causing the jaws to hold the heel.

10 12. In a machine of the class described, the combination of a cutter, a rest for the tread face of the heel, shoe holding jaws on the rest, means for moving the rest past the cutter to cause operation of the cutter upon the breast of the heel of the shoe, and means for causing the force required to move the rest to be effective to cause the jaws to hold the shoe.

15 13. In a machine of the class described, the combination of breasting means, a plate to engage the tread face of a heel attached to a shoe to be acted upon by said breasting means, and means mounted on the plate to engage the breast face of the heel engaged by the plate and to locate the heel longitudinally, said means being constructed and arranged to engage only the central portion of the breast edge.

20 14. In a machine of the class described, the combination of a rotary cutter, a shoe rest against which the tread face of a shoe heel is held by the operator, means for relatively moving the cutter and rest to cause operation of the cutter on the breast of the heel, means on the rest to engage the central portion only of the breast edge of the top lift, and means for maintaining said means in central relation to said edge irrespectively of the width of the heels being operated upon.

25 15. In a machine of the class described, the combination of a rest for the tread face of a heel, a gage on the rest to engage the centre of the breast edge of the top lift of the heel, jaws constructed and arranged to be closed upon the sides of the heel, and connections between the gage and said jaws to locate the gage centrally of the heel held by the jaws irrespectively of the width of the heel.

30 16. In a machine of the class described, the combination of breasting means, a plate to receive the tread face of the heel of a shoe, means adjacent to the plate to engage only the central portion of the breast edge of the heel to locate the heel longitudinally of the shoe, heel embracing members one of which is movable to hold the heel, and means

controlled by said movable member to maintain said breast engaging means centrally of the breast irrespectively of the width of the heel embraced by said members.

35 17. In a machine for breasting a Louis heel attached to a shoe and having a scallop in its breast adjacent to the top lift, a rotary cutter, a work support between which and the cutter there is relative movement to cause the heel to be breasted from side to side of the heel, and a gage constructed and arranged to lie in the scallop of the heel breast out of the way of the cutter to locate the heel relatively to the cutter and to allow action of the cutter upon the heel breast up to the outer corners of the scalloped portion.

40 18. In a machine of the class described, the combination of a rotary cutter, a shoe rest against which a shoe is held by the hand of the operator, means for locating the heel vertically relatively to said rest, means for relatively moving the cutter and the rest to cause operation of the cutter upon the breast of the heel of the shoe in a direction from side to side of the heel, and means for arresting said relative movement when the axis of the cutter and the side of the heel on which the cutting action is finished are in the same plane.

45 19. In a machine of the class described, the combination of a rotary cutter, a shoe rest against which a shoe is held by the hand of the operator, means for relatively moving the cutter and the rest to cause operation of the cutter upon the breast of the heel of the shoe in a direction from side to side of the heel, means for arresting said relative movement when the axis of the cutter and the side of the heel on which the cutting action is finished are in the same plane, and means for retarding said relative movement of the shoe and cutter as the cut approaches completion.

50 20. In a machine of the class described, the combination of a rotary cutter, a shoe support, a guide in which the shoe support is movable vertically past the cutter for the action of the cutter upon the breast of a shoe heel, means arranged for fine adjustment to vary the relative location of the cutter and the guide in a horizontal direction longitudinally of the cutter axis to control the depth of the cut effected by the cutter lengthwise of the heel, and a fine adjustment to limit relative approaching movement of the cutter and guide heightwise of the heel and to control action of the cutter on the shank portion of the heel breast.

In testimony whereof I have signed my name to this specification.

DARIUS W. BUNKER.
